Cook Stove.

Patented Apr. 11. 1835.

Thaddeus Fairbanks of St Johnsbury Vermont

Letter Patent

the Schedule referred to in this Letter Patent and making part of the same containing a description in the words of the said Thaddeus Fairbanks himself of his improvement in the Backing Stove.

To all to whom these presents shall come, to wit it is known that I, Thaddeus Fairbanks of St Johnsbury in the County of Caledonia and State of Vermont have invented certain improvements in the mode of constructing stoves for cooking and for warming apartments and that the following is a full and exact description thereof. The stove upon which my improvements are made is of the kind known in many places under the name of the Diving Stove and which is so called in consequence of the draft being directed afterwards from the fire, before the smoke and heat are made thus out through the ordinary pipe. This stove is best adapted to the burning of wood, and may be made either square or oval, having the general form of the common top plate stove. The upper part of the stove forming the fire place beneath this is the oven, the lower part of which constitutes the upper part of a flue, formed between it and the bottom plate of the stove. The door for the supply of fuel is best made at one end, the diving or descending flue which leads to that below the oven being at the other end, a plate which at the end of the fire place forming its back, its upper edge receding at a sufficient distance below the top plate to allow the flame, smoke to pass over it into the back flue.

Openings are made through the top plate to serve cooking utensils. The diving flue leading from the back flue to the stove pipe is formed by making an opening from the said lower flue through the side plate of the stove, near its front end which opening is covered by a curved plate leading from the bottom to the top of the stove above this being connected with the common stove pipe, it generally goes to the curved plate forming this diving flue an inclination towards the back end of the stove so that it may terminate and connect with the pipe at about the middle of the side plate. This diving flue formed

by the curved plate as above described constitutes one of my improvements. It is sometimes desirable to allow the draft to escape directly from the fire place into the flue, without passing down and under the oven. To effect this I make an opening from the fire place through the plate into the flue and to this I adapt a valve or damper which when open allows the direct escape and when closed guides the draft underneath the oven. This constitutes my second improvement. What I claim therefore as my invention is, the before described wing flue formed by the curved plate combined with the valve or damper operating in the way and for the purposes described, not intending to claim in any manner the general construction of the stove with a driving flue nor any of the individual parts that I have described with the exception of that which I have above designated as constituting my improvement.

I do testimony that the foregoing is a full and accurate description of my improvement I have hereunto subscribed my hand this fourteenth day of March A.D. 1835.

Signed

Wm. F. Wirtz
